UNITED STATES PATENT OFFICE.

JOHN J. NOONAN, OF ST. LOUIS, MISSOURI.

LOOSE-LEAF BOOK.

1,115,964.

Specification of Letters Patent.

Patented Nov. 3, 1914.

Application filed October 20, 1913. Serial No. 796,112.

To all whom it may concern:

Be it known that I, JOHN J. NOONAN, a citizen of the United States of America, and a resident of the city of St. Louis and State 5 of Missouri, have invented certain new and useful Improvements in Loose-Leaf Books, of which the following is a full, clear, and exact description, reference being had to the accompanying drawings, forming a part of 10 this specification.

My invention relates to a loose leaf book and one of the objects is to produce an improved book of this kind having a book section adapted to receive loose leaves on both 15 of its sides, and cover sections movable to cover either one or both sides of said book section. The loose leaf holder is preferably so constructed that the leaves on one side of the book section may be readily transferred 20 to the other side of said section, and the cover sections may be shifted to expose the leaves at either side of said book section.

Another object of the invention is to provide a strong, simple and inexpensive loose 25 leaf holder.

Figure I is an elevation looking toward the edges of the book sections, showing said sections unfolded. Fig. II is a perspective view showing the book sections folded to 30 cover the loose leaves at one side of the inner section and to expose the loose leaves at the opposite side of said inner section. Fig. III is a perspective view showing the book sections folded to expose the leaves that are 35 covered in Fig. II. Fig. IV is an enlarged vertical section illustrating the upper end of the inner book section, and the loose leaf holder secured to said section.

In the accompanying drawings: 1 designates 40 an inner book section, preferably made of stiff material serving as a backing for the loose leaves. A back cover section 2 is hinged at 3, (Fig. I), to the lower end of the inner section, and a front cover section 4 is hinged at 5 to the lower end of the back cover section 2.

Briefly stated, my book preferably includes an intermediate section 2 and end sections 1 and 4 hinged to the ends of said 50 intermediate section. The free end of the inner end section 1 is provided with arched fingers 6 and 7, projecting from opposite sides of said section and extending over the upper edge thereof. The upper margin of 55 the inner section 1 is preferably a sheet metal member bent to form a housing hav-

ing opposing walls 8 and 9, the free end 10 of said sheet metal member being located directly above the main body portion of the inner section 1. Each of the walls 8 and 9 is provided with an aperture for the reception of a finger member and the rigid finger member 7 extends through both of said apertures, said rigid finger member being rigidly secured in position by upsetting its 60 end against the wall 9. The rigid finger member is provided with a shoulder 11 engaging the wall 8. The movable finger 6 extends through the aperture in the wall 9 and is secured to the sheet metal housing by 65 the upset end of the finger 7 which lies in the upper portion of the aperture in wall 9. The arched fingers 6 and 7 engage each 70 other at 12, and the finger 6 is movable toward and away from the finger 7. The finger member 6 is formed with a curved paper holding finger and an inclined latch finger 14, said member being offset to produce an abutment shoulder 13 which lies between the inclined latch finger and the curved 75 paper holding finger. The inclined latch finger 14 and the abutment shoulder 13 are interposed between and closely fitted to the housing walls 8 and 9. When the finger member 6 is moved from the position shown 80 in full lines, Fig. IV, to the position shown in dotted lines, the inclined end portion of said finger swings between the walls 8 and 9, thereby spreading said walls, the wall 9 being yieldable to permit the finger to rock 85 and to hold the finger in either of the positions shown in Fig. IV. The wall 9 engages the shoulder 13 to serve as a fulcrum for the movable finger member 6.

The loose leaves are perforated to receive 90 the arched fingers and while held by these fingers the leaves may be transferred from one side of the inner book section 1 to the other side thereof. The cover sections 2 and 4 may be moved from the position, 100 shown in full lines Fig. I, to the position shown in dotted lines, thereby covering the leaves 15 and permitting the leaves 16 to be exposed by lifting the cover section 4. Or, if desired, the cover sections may be shifted 105 to cover the leaves 16 and uncover the leaves 15. The arched fingers 6 and 7 extend from both sides of the inner book section 1, so that the leaves on both sides of said section are properly supported for writing purposes.

The blank leaves may be initially sup-

ported at one side of the inner book member 1 and afterward transferred, as used, to the opposite side thereof for future reference. When so used, the transferred leaves 5 15 shown in Fig. II will be found in their numerical or chronological order by shifting the parts from the position shown in Fig. II to the position shown in Fig. III. The top leaf shown in Fig. III is the first 10 leaf transferred, and the remaining leaves follow in their proper order.

I claim:

1. A loose leaf book comprising an inner section 1 provided with loose leaf supports 15 in the form of arched fingers extending around one of its edges and adapted to support loose leaves on one or both sides of said inner section, and adapted to hold the leaves while they are being transferred from one to 20 the other side of said inner section; a back cover section 2 hinged to the lower edge of said inner section 1, a front cover section 4 hinged to the lower edge of said back cover 25 section 2, the back cover section being arranged directly between the inner section and the front cover section when the sections are unfolded so that the two cover sections may be shifted to cover the leaves at either side or both sides of said inner section, or to expose the leaves at either side or 30 both sides of said inner section.

2. A loose leaf book comprising an inner section provided with a loose leaf holder 35 adapted to hold loose leaves at both sides of said inner section and adapted to hold said loose leaves while they are being transferred around an edge of said inner section; combined with a back cover section hinged to an

edge of said inner section, and a front cover section hinged to said back cover section, the 40 back cover section being so connected to the inner section that the said front and back cover sections may be shifted to cover the leaves at either side or both sides of said inner section or to expose the leaves at either 45 side or both sides of said inner section.

3. A loose leaf holder comprising a support provided with opposing walls one of which is yieldable, each of said walls having an aperture for the reception of a finger, a movable finger extending through and loosely mounted in one of said apertures, and a fixed finger extending through both of said apertures and rigidly secured to said support, the said fixed finger being arranged in the aperture containing the movable finger so as to serve as means for securing said movable finger to said support. 50

4. A loose leaf holder comprising finger members one of which is movable, a support for said finger members provided with an aperture in which the movable finger member is mounted, said movable finger member consisting of a paper holding finger and an inclined latch finger extending therefrom, and the said movable finger member being offset to produce an abutment which lies between the latch finger and the paper holding finger, and said support being provided with a fulcrum adapted to be engaged 55 60 65 70 by said abutment.

JOHN J. NOONAN.

In the presence of—

CHR. G. KUEBLER,

HECTOR E. DASMEFOS.
